UNITED STATES PATENT OFFICE.

EMIL EINFELDT, OF DAVENPORT, IOWA, ASSIGNOR TO BETTENDORF
METAL WHEEL COMPANY, A CORPORATION OF IOWA.

METHOD OF MAKING METAL WHEELS.

No. 810,198.

Specification of Letters Patent.

Patented Jan. 16, 1906.

Original application filed October 20, 1904, Serial No. 229,222. Divided and this application filed March 13, 1905. Renewed December 8, 1905. Serial No. 290,963.

To all whom it may concern:

Be it known that I, EMIL EINFELDT, of Davenport, county of Scott, and State of Iowa, have invented a new and useful Improvement 5 in Methods of Making Metal Wheels, of which the following is a specification, being a division of original application filed October 20, 1904, Serial No. 229,222.

This invention relates to the manufacture 10 of metal wheels of the type known in the art as "staggered wheels"—that is, wheels wherein the spokes are fastened to the hub in two rows or ranks and are secured to the rim either in a single row or in two rows approaching each other more or less.

The object of the invention is to produce a wheel of this character in which all the spokes will be under a uniform and even tension; and the invention consists of the improved method 20 of accomplishing this result, which method consists in first fastening all the spokes of one rank to the hub and the rim and then fastening the spokes of the other rank to the members of the wheel while the spokes of the second rank are hot, preferably at their ends, with the result that the contraction of the spokes due to their cooling will cause the hub to move endwise a slight distance relatively to the rim, which movement of the hub will 30 continue until the resulting strain placed on the spokes of the first rank balances that which the contracting spokes exert, when the hub will come to a rest and all the spokes of both ranks will be under a uniform and evenly-distributed tension. For the best results care should be taken that after the first rank of spokes has been fastened in place the hub will occupy such a position with reference to the rim in a direction longitudinally 35 of the axis of the hub that after it has been moved endwise by the contraction of the second rank of spokes and has come to a rest it will be properly and accurately centered. The method of procedure described contemplates 40 the fastening of only the second rank of spokes while their ends are hot, and the contraction of this rank only is utilized to place a strain or tension on all the spokes. Hence under this broad comprehension of the invention the first 45 rank of spokes may be fastened in cold and by any suitable means either to a rim which has had its ends previously connected together or to an open rim which must be con-

nected after the first rank has been fastened in place. I may, however, with a closed rim 55 fasten both ranks of spokes in place while their ends are hot, allowing the first rank to cool sufficiently to permit their contraction before the second rank is secured. As a result of this mode of procedure when the spokes 60 first secured contract they in shortening will pull on the hub and rim and will cause the hub to move relatively to the rim some distance endwise, and this movement of the hub meeting with no counter resistance the tension 65 of the spokes will be slight and the hub will be carried to a point beyond that it will finally occupy in the completed wheel. When, however, the second rank of spokes has been secured to the members of the wheel, their 70 shortening, due to cooling, will meet with the resistance offered by the first rank, and while a free movement of the hub in an opposite direction will not be permitted it will be moved until the strain of the contracting spokes is 75 balanced by the increasing tension which this reverse movement of the hub places on the spokes of the first rank.

In the accompanying drawings, Figure 1 is a perspective view of a rim of the form which 80 I prefer to employ in carrying my invention into effect. Fig. 2 is a side elevation of the hub. Fig. 3 is an elevation of one of the spokes. Fig. 4 is a view showing the parts of the wheel assembled previous to the fastening operations and illustrating the relations they occupy to the fastening devices. Fig. 5 is a view showing the relation of the hub and rim and spokes after the first rank of spokes has been fastened in place. Fig. 6 is a sectional elevation of the completed wheel, showing the hub properly centered after it has been moved endwise by the contraction of the second rank of spokes. Fig. 7 is a view in the nature of a diagram showing the 85 relative movement of the hub due to the contraction of the second rank of spokes. Fig. 8 is a similar view showing the relative opposite movements of the hub due to the contraction of the two ranks of spokes when both 90 ranks are fastened in hot.

Referring to the drawings, in carrying my invention into practice I prefer to fasten the spokes to the hub and rim in such manner that there will be no change in the length of 105 the spokes between these members, with the

result that there will be no danger of destroying the true circular form of the rim. This admits of the employment of a rim having its ends connected previous to the fastening 5 of any of the spokes thereto. In the accompanying drawings I have illustrated a rim of this character and mechanism which will secure the spokes in place in this manner. It will be understood, however, that my invention 10 may be carried out by other means, the essence of the invention residing not in the manner of securing the individual spokes in place, but in fastening the two ranks of spokes in separately and utilizing the contraction of the second rank to place all the spokes under tension, the ends of the rim being fastened together before the second rank of spokes is put in.

I will now describe a method of carrying 20 out my invention which in practice I have found to accomplish to an admirable degree the result to be attained.

I provide first a closed rim A, Fig. 1, formed at intervals with holes $a a' a'' a'''$, &c., 25 extending in a single row therearound to receive the outer ends of the spokes B. (Represented in Fig. 3.) I next provide a hollow hub or shell C, Fig. 2, having near one end a series of holes $c c' c'' c'''$, &c., for the inner ends of 30 the spokes of one rank, and near the opposite end a series of holes $d d' d'' d'''$, &c., for the inner ends of the spokes of the other rank. The spokes B, as shown in Fig. 3, are provided near their inner ends with a shoulder b and at 35 their opposite ends are thickened, as indicated at b' . Previous to the fastening of a spoke in place the parts of the wheel are assembled in the relations shown in Fig. 4, with the hub sustained in fixed relations to the 40 rim in the diametrical center of the same and the spoke with its inner end extending through a hole of one rank in the hub, its outer thickened end extending through a hole in the rim, and the shoulder b seated 45 against the outer face of the hub. A heading device E for the inner end of the spoke extends within the hub in position to act on the end of the spoke therein. A heading device F extends outside the rim in position to 50 act on the outer end of the spoke projecting therethrough. A shoulder-forming clamp G embraces the spoke at the end of the thickened portion of the same at the inner face of the rim in position to act on the spoke at this 55 point, while a stop-clamp H embraces the spoke at the outer face of the shoulder b . By suitable means the heading-tool E is advanced, upsets the end of the spoke within the hub, thereby forming a confining-head 60 thereon, and immediately retreats, the spoke and the hub during this operation being held firmly against motion in the direction in which the header acts by means of the spoke-clamp H, against which the shoulder b abuts. 65 The header F is now by suitable means ad-

vanced toward the hub and upsets the outer end of the spoke, thereby forming a head, simultaneously with which action the rim, hub, and spoke are pushed endwise at less speed than the header F and with relation to the 70 clamps G, with the result that the thickened portion of the spoke at b' is scraped up by the frictional resistance offered by the clamps G, and this scraped-up portion of the spoke is accumulated in the form of a shoulder K and is disposed in forcible contact with the inner face of the rim. The hub and rim, connected by the spoke just fastened, is now shifted around to bring the next hole in the hub in position for another spoke, which is 80 seated in place with its outer end extending through the next alternate hole in the rim and its inner end through the next hole of the same rank in the hub. The operation of fastening the spoke just described is repeated, 85 resulting in the attachment of the second spoke, and these operations are continued until all of the spokes of one rank have been secured in succession entirely around the wheel. The partly-completed wheel with one rank 90 of spokes fastened in place is now acted on by the mechanism described, and the spokes of the second rank are fastened successively in position, with their inner ends extending through the holes of the second rank in the 95 hub and their outer ends extending, respectively; in the holes in the rim left between the spokes of the first rank, each spoke of the second rank, however, before being acted on by the fastening devices having its 100 ends heated to the proper degree. When the spokes of the second rank cool, they in shortening from contraction will draw the hub endwise, which action will place a strain on the spokes of the first rank, and this will 105 continue until it balances, the strain being exerted by the contracted spokes, whereupon the parts of the wheel will come to a rest, and the tension will be evenly distributed among all the spokes of both ranks. 110 The relation of the hub, rim, and connected spokes of the first rank should be such that when the hub is moved endwise by the contraction of the spokes of the second rank and comes to a rest the hub will occupy its 115 proper relation in a longitudinal direction to the rim.

In Fig. 5 the relation of the parts of the unfinished wheel is illustrated. Here it will be seen that the hub is held by the connected spokes a slight distance beyond its final true position in the completed wheel, which true position is shown in Fig. 6, where it will be seen that by the contraction of the second rank of spokes the hub has been 120 drawn to its proper point.

In Fig. 7 the dotted line and the arrow illustrate, respectively, the position of the hub after the first rank has been fastened and its final position after the second rank 130

has been secured and its spokes have contracted.

Instead of fastening the spokes of the first rank in place by the means described and to a closed rim they may be secured to an open rim and by any suitable means by which the members of the wheel will be connected together ready to have the second rank fastened in hot, it being understood, of course, that the rim will have its ends connected together after the first rank of spokes has been fastened.

As before stated, both ranks of spokes may be fastened to the hub and rim while the ends of the spokes are hot, time being given for the spokes of the first rank to contract before the second rank is applied. In proceeding in this manner I employ a closed rim from the start and fasten the spokes in place by means which in the fastening operation will not change the length of the spokes between the hub and the rim. After the first rank has been fastened in this manner with the ends of the spokes hot time is given to permit them to cool sufficiently, the result being that their contraction will act to draw the hub endwise beyond the point it will finally occupy in the completed wheel, which abnormal position of the hub is indicated by the dotted arrow in Fig. 8. When the spokes of the second rank after being fastened in place hot have cooled and contracted, they will act to draw the hub back in an opposite direction, as indicated by the full-line arrow, Fig. 8, a distance which in practice has been found to be one-half that which the hub was drawn by the contraction of the first rank of spokes. As a result of this reverse movement of the hub under the contraction of the second rank all the spokes will be placed under an even and uniform tension, and the hub will finally come to rest at its proper and true position with relation to the other parts of the wheel.

Having thus described my invention, what I claim is—

1. The method of making metal wheels in which the spokes are secured to the hub in two ranks, which method consists in fastening all the spokes of one rank to the members of the wheel and then fastening the spokes of the other rank while hot, the rim

being closed at any time prior to the fastening of the second rank.

2. The method of making metal wheels in which the spokes are secured to the hub in two ranks, which method consists in fastening together the hub, rim and spokes of one rank in such relations that the hub will occupy a position in a longitudinal direction beyond that it will occupy in the completed wheel, then fastening all the spokes of the other rank to the hub and closed rim while said spokes are hot; whereby the contraction of the spokes from cooling will draw the hub to the proper position and will place all the spokes under tension.

3. The method of making metal wheels in which the spokes are fastened to the hub in two rows or ranks, which consists in providing a hub with two rows of holes therearound, and a rim with holes spaced therearound at intervals, fastening all the spokes of one rank in place with their inner ends in the holes of one rank in the hub and their outer ends in every alternate hole in the rim, then fastening all the spokes of the other rank in place while hot with their inner ends in the holes of the second rank in the hub and their outer ends in the holes in the rim, the rim being closed at any time prior to the fastening of the second rank.

4. The method of making staggered wheels, which consists in fastening one rank of spokes to the hub and rim while the spokes are hot, allowing the secured spokes to contract, and then fastening the spokes of the other rank while hot, to the members of the wheel, the rim being closed at any time prior to the fastening of the second rank.

5. The method of making staggered wheels, which consists in providing a hub with two series of holes therearound, a closed rim, and spokes, fastening all the spokes of one rank to the hub and rim respectively, and then securing the spokes of the other rank while hot to the hub and rim.

In testimony whereof I hereunto set my hand, this 11th day of March, 1905, in the presence of two attesting witnesses.

EMIL EINFELDT.
